United States Patent Office.

JAMES SPEAR, OF PHILADELPHIA, PENNSYLVANIA.

Design No. 2,803, dated October 15, 1867.

DESIGN FOR A STOVE.

The Schedule referred to in these Letters Patent and making part of the same.

TO ALL WHOM IT MAY CONCERN:

Be it known that I, JAMES SPEAR, of the city and county of Philadelphia, and State of Pennsylvania, have originated and designed a new Ornamental Pattern for Stove-Plates, of which the following is a full, clear, and exact description, reference being had to the accompanying photograph, with letters marked thereon, making part of this specification.

Figure 1 is a perspective view of the stove.

Figure 2 is the outline of the shape of the screen-work surrounding the cylinder.

Figure 3 is a transverse section of one of the four sides of the base-plates A A.

The ornament B B is the same on all four sides of the base, and consists of fine fluted work, surrounded with scroll and drapery work combined with a small-corded tassel at the centre C C. The open-work screen around the cylinder F consists of scroll-work ornamented on the outer surface O O with cord-and-tassel-work carving thereon. The plates D D of the top section are ornamented with fine fluting covered with drapery, cord-and-tassel work carved thereon. The crown-top E is ornamented with drapery and tassel-work carved thereon.

What I claim as my invention, and desire to secure by Letters Patent, is—

The design for ornamentation of stoves, substantially as shown and described.
